CLAIM

The ornamental design for an exoskeletal member of an ultrasound platform, as shown and described.

DESCRIPTION

This application is related to U.S. patent application Ser. No. 29/284,463 entitled "Ultrasound Platform," the disclosure of which is hereby incorporated herein by reference.

FIG. 1 is an isometric view of an exoskeletal member of an ultrasound platform;

FIG. 2 is a front elevation view of FIG. 1;

FIG. 3 is a back elevation view of FIG. 1;

FIG. 4 is a left elevation view of FIG. 1;

FIG. 5 is a right elevation view of FIG. 1;

FIG. 6 is a top plan view of FIG. 1; and,

FIG. 7 is a bottom plan view of FIG. 1.
